UNITED STATES PATENT OFFICE.

CHARLES GRANT HARRIS, OF NILES, OHIO, ASSIGNOR TO THE HARRIS AUTOMATIC PRESS COMPANY, OF NILES, OHIO, A CORPORATION OF OHIO.

PRINTING-PRESS.

No. 862,249.

Specification of Letters Patent.

Patented Aug. 6, 1907.

Application filed February 14, 1906. Serial No. 301,062.

To all whom it may concern:

Be it known that I, CHARLES GRANT HARRIS, of Niles, in the county of Trumbull and State of Ohio, have invented certain new and useful Improvements 5 in Printing-Presses; and I do hereby declare the following to be a full, clear, and exact description of the invention, such as will enable others skilled in the art to which it appertains to make and use the same.

Lithograph printing is ordinarily performed by stop 10 cylinder presses. In consequence, the output is not very great, since the impression cylinder has to remain idle while the traveling flat stone is being returned.

According to my invention the stone is approximately semi-cylindrical, and is so mounted that the 15 lines of pressure will be uniformly toward a central fixed bearing, and in consequence the stone is not only held as against displacement, but is free from all liability to break. The reduction of the stone's surface does not interfere with its relation to such bearing, all such reductions being compensated for between the stone and 20 the body of the cylinder of which it forms a part.

The invention will be hereinafter fully set forth and particularly pointed out in the claims.

In the accompanying drawings, Figure 1 is a vertical 25 sectional view, parts of a press being conventionally indicated. Fig. 2 is a longitudinal sectional view of the printing cylinder. Fig. 3 is a view in perspective thereof, with the stone section removed. Fig. 4 is a 30 similar view of the stone. Fig. 5 is an end view showing the extent to which the stone section may be reduced.

Referring to the drawings, 1 designates the frame of 35 a printing press, a portion only being shown; 2 the inking rollers; 3 the water rollers; 4 the feed rollers, and 5 the impression cylinder.

6 is the printing cylinder. It is composed in part of metal and in part of stone, the latter occupying about one-half the circumference. The metallic portion consists of a body 7 having two circular end disks 8 40 from which project the journals 9. Concentrically mounted on disks 8, and working in screw threads thereof, are the stone-retaining rings 10, which on their inner, opposite faces, carry wedge-like ribs 12. The thread of one disk is a right-hand thread and that of the other a 45 left-hand, so that any tendency of the stone to turn axially when engaging the impression cylinder will cause the rings 10 to tighten. Extending longitudinally of body 7, on the flat face thereof, at or about the axis of the cylinder, is a key or spline 13 preferably 50 formed with straight parallel sides.

14 is the stone section. It is approximately semi-circular in cross-section, and fits against the flat face of body 7 and between the end disks. The radius of the

stone is slightly greater than that of the metallic body 7, which latter is not intended to engage the impression 55 cylinder. In the ends of the stone are V-grooves 15 which receive ribs 12, so that when the rings 10 are moved inwardly said ribs will enter the grooves and bear against the inner beveled walls thereof, holding the stone firmly in place. In the flat face of the stone is 60 formed a longitudinal cut-out, curved approximately concentric to the working face of the stone. This cut-out accommodates a semi-circular bar 16, in the flat face whereof is a longitudinal groove which conforms to the key 13. All pressure against the face of the 65 stone is communicated directly against the smooth curved face of the bar 16, and in consequence there is no line on which the stone might be broken off. As the face of the stone is reduced from time to time by planing, the radius of the stone is maintained by moving it 70 outwardly away from the metallic body 7. This is preferably accomplished by interposing filler plates 17 between the stone and the flat face of the body, thereby uniformly building out the stone and the pressure-receiving bar 16. Other means may, however, be employed for compensating for the wear of the stone. Additional fillers may be added as the stone is still further reduced, the extent of so building up the stone section 75 being limited only by the interlocking of bar 16 with the key. This will be readily understood by reference 80 to Fig. 5 wherein several superposed plates 18 are shown.

In practice, all pressure against the face of the stone is communicated directly to the bar 16 and through it to the key. Not only is the stone locked at its ends, but it is locked and braced at a common central point 85 toward which are directed all lines of pressure. In consequence, the stone cannot be deflected by contact with the impression cylinder, and furthermore there is no danger of its being broken by such contact. If desired, the construction of the central locking means may 90 be varied, but best results are attained by avoiding all sharp angles.

The planing of the face of the stone is effected by mounting it on a cylinder the counter-part of what has been described, such cylinder forming part of a planing machine. The extent to which the stone is to be reduced by planing is controlled by the introduction of the proper number of filler plates beneath it before the planing is begun. As the cylinder is revolved the face of the stone will be engaged by a suitable knife and the necessary reduction effected. When the stone is replaced in the press, such reduction is compensated for by the filler plates 18, and the inner walls of the grooves in the ends are also planed the necessary extent to allow the ribs 12 to engage therewith. A lithographing cylinder thus constructed may be employed 105

in a rapidly operated cylinder press, and is especially designed for the style of press known as the Harris Automatic.

I claim as my invention:—

- 5 1. In a rotary printing press, a cylinder having a stone segment, and a bearing for the stone at or about the axis of the cylinder for receiving all lines of pressure against the segment, said bearing being curved substantially concentric to the face of the stone segment.
  - 10 2. In a rotary printing press, a cylinder having a stone segment, and a fixedly held bar having a smooth curved face forming a bearing for the segment.
  - 15 3. In a rotary printing press, a cylinder composed in part of stone, which occupies about one-half the circumference, a curved seat for said stone and means for locking the stone against said seat.
  - 20 4. In a rotary printing press, a cylinder composed of two sections, one section being of metal and the other of stone, and means for interlocking the two sections at or about the axis of the cylinder, comprising a bearing surface curved substantially concentric to the face of the stone.
  - 25 5. A cylinder composed of two sections, one section being of metal and the other of stone, means for interlocking the two sections at or about the axis of the cylinder, and means engaging the stone section for binding and holding it fixedly relative to said interlocking means.
  - 30 6. A cylinder composed of two sections, one section being of metal and the other of stone, said metal section having a key or spline extended longitudinally thereof and a seat for said stone engaged by said key, said seat being curved substantially concentric to the face of the stone.
  - 35 7. A cylinder composed of two sections, one section being of metal and the other of stone, said metal section having a key or spline extended longitudinally thereof, and a bar having a groove to accommodate said key, said bar fitting in said stone section.
  - 40 8. A cylinder composed of two sections, one section being of stone and formed on a slightly greater radius than the other section, means forming an interlocking connection between the two sections, and fillers interposed be-
- tween the two sections for compensating for any wear or reduction in the face of the stone section.
9. A cylinder composed of two sections, one section being of stone and formed on a slightly greater radius than the other section, a key or spline for locking said stone section, and separate fillers interposed between the two sections for compensating for any wear or reduction in the face of the stone section.
  10. A cylinder composed of a metallic body and a stone section, means for interlocking said body to the stone section at their meeting faces, and means for holding the said stone section in engagement with said interlocking means, comprising binding rings engaging said stone section at its ends, said rings being movable in opposite directions.
  11. A cylinder composed of a metallic body and a stone section, means for interlocking said body and stone section at their meeting faces, said body having end disks oppositely threaded on their peripheries, and binding rings axially adjustable on said disks, said rings holding said stone section in engagement with said interlocking means.
  12. A cylinder composed of a metallic body, a stone section having a curved cut out, a bar fitted in said cut out and having a groove with opposite straight walls, a key or spline on said body fitting in said groove, means engaging the ends of the stone section for holding it in place, and filler plates interposed between the flat faces of the two sections.
  13. The combination with the body having a flat face, a key or spline extended longitudinally of such face and end disks, of a stone section also having a flat face, a bearing bar for said stone section interlocking with said key or spline, said stone section having grooves in its ends, and binding rings on said disks having ribs for engaging said grooves.
- In testimony whereof, I have signed this specification in the presence of two subscribing witnesses.

CHARLES GRANT HARRIS.
